UNITED STATES PATENT OFFICE

JOHN WILLIAM NASMITH, OF HEATON MERSEY, MANCHESTER, ENGLAND

COMBING MACHINE FOR TEXTILE FIBERS

Application filed December 11, 1929, Serial No. 413,341, and in Great Britain August 13, 1929.

The invention relates to rollers in combing machines for textile fibers, of the Heilmann type.

In combing machines of the type to which I have referred the leather detaching rollers of say six different combing heads are usually lifted from and lowered upon the combing cylinder segment by means of a shaft oscillating around its longitudinal axis, a lever at each combing head being carried upon the shaft and itself carrying the leather detaching roller bearings. The rollers and their weights are liable to cause torque in such shaft, with resultant unevenness of timing in the detaching, and, to obviate this, extra shaft-oscillating means have been provided along the shaft.

The object of the present invention is a means whereby a shaft may be operated to lift any desired number of detaching rollers distributed along its length, the possibility of torque in the shaft being entirely eliminated.

According to the invention and with this object in view the weight to be lifted is carried upon a fulcrumed lever or fulcrumed bars, and a rod is provided which is movable in the direction of its length, with parts interposed between the said rod and the plurality of levers to lift or lower the latter, and their borne weights, according to the direction in which the rod is moved.

The interposed parts may be fulcrumed bell crank levers which, on longitudinal movement of the rod, lift or lower as the case may be a bar which in turn lifts the ends of the roller-bearing levers.

To adjust the timing of the lift, the bar just referred to may be made adjustable as to its surface, as by adjustable screws borne on the said surface which screws make contact with the lever ends to be lifted.

Each lever for each weight may be a three-armed lever, the end of one arm thereof serving as the fulcrum point, the second arm bearing the roller, and the end of the third arm taking the thrust of the bar referred to above.

The invention as applied to a combing machine for the lifting of a plurality of leather

covered detaching rollers will now be fully described, with suitable constructional details as above set forth. Reference will be had to the drawings hereto annexed, in which Figure 1 is an elevation of one detaching roller and the lifting means, with the operating rod and accessories, and Figure 2 is a view at right angles to that of Figure 1.

Referring to the figures a rod 3 is provided slidably fitted in suitable bearings of any convenient form, and slides longitudinally as desired by any convenient means—not shown—for instance a groove cam in which the end of the rod suitably engages. At each combing head of the machine is fulcrumed a bell crank lever 4 the lower extremity of which abuts against an adjustable block 5 fitted upon the rod 3 by means of an anti-friction bowl 6 mounted on the lever. The other arm of each such lever 4 carries a further anti-friction bowl 7 which makes contact with a bar 8, fitted in suitable bearings which allow vertical movement thereof, the said bar being parallel to the rod 3; and on the upper face of such bar are fitted in tapped holes, adjustable screws 9 with nuts 10.

At each combing head is fulcrumed a three-armed lever one arm 11 of which is fulcrumed upon a shaft 12. A vertical arm 13 bears at its upper extremity bearings for a detaching roller 14; and the third arm 15 of the said lever is provided with an anti-friction bowl 16 which rests upon one of the adjustable screws 9 upon the bar 8. Two levers are employed as shown to support the bearings for a roller 14.

The weighting of a roller may be effected by means of springs 17 or by any suitable weight, acting upon a lever 18 which is as to form and construction, identical with the other three-armed lever and is bifurcated to fit upon the shaft 12.

Where a lever arm is bifurcated for fulcrumming as shown—a convenient construction for fitting and removal—a stop such as shown in Figure 2 is provided, this stop consisting of an adjustable screw 19 threaded through a tapped projection 20 on the machine framing. As shown, this stop contacts

with the weighting lever 18, and prevents loose movement thereof on its fulcrum point as it descends.

I claim:—

5. 1. In a combing machine, a detaching roller, fulcrumed lever bearings for such roller, a rod movable in the direction of its length, and means for converting any such longitudinal movement of the rod into movement of the roller-bearing levers around their fulcra.
10. 2. In a combing machine, a detaching roller, fulcrumed lever bearings for such roller, a rod movable in the direction of its length, a bar parallel to the rod but movable at right angles to such rod, supporting means upon such bar for the free ends of the roller-bearing levers, and means for converting longitudinal movement of the rod into transversal movement of the bar.
15. 3. In a combing machine, a detaching roller, fulcrumed lever bearings for such roller, a rod movable in the direction of its length, a bar parallel with the rod but movable at right angles to such rod, supporting means upon such bar for the free ends of the roller-bearing levers, and operating bell crank levers fulcrumed between the rod and bar and controlled by longitudinal movement of the first rod.
20. 4. In a combing machine, a detaching roller, fulcrumed lever bearings for such roller, a rod movable in the direction of its length, a bar parallel with the rod but movable at right angles to the length of such rod, adjustable supporting means between the bar and the free ends of the roller-bearing levers, and means for converting longitudinal movement of the rod into transversal movement of the bar.
25. 5. In a combing machine a detaching roller, fulcrumed lever bearings for such roller, a rod movable in the direction of its length, a bar parallel with the rod but movable at right angles to the length of such rod, adjustable supporting means between the bar and the free ends of the roller-bearing levers, and operative bell crank levers fulcrumed between the rod and bar and controlled by the sliding rod movement.
30. 6. In a combing machine, a detaching roller, fulcrumed lever bearings for such roller, a rod movable in the direction of its length, means for converting any such longitudinal movement of the rod into movement of the roller-bearing levers around their fulcra, and a weighting lever fulcrumed upon a bearing lever fulcrum and engaging the detaching roller.
35. 7. In a combing machine, a detaching roller, fulcrumed lever bearings for such roller, a rod movable in the direction of its length, a bar parallel to the first but movable at right angles to such rod, supporting means upon such bar for the free ends of the roller-bearing levers, means for converting longitudi-
- dinal movement of the rod into transversal movement of the bar, and a weighting lever fulcrumed upon a roller-bearing lever fulcrum and engaging the detaching roller.
40. 8. In a combing machine, a detaching roller, fulcrumed lever bearings for such roller, a rod movable in the direction of its length, a bar parallel with the rod but movable at right angles to such rod, supporting means upon such bar for the free ends of the roller-bearing levers, and a weighting lever fulcrumed upon a bearing lever fulcrum and engaging the detaching roller.
45. 9. In a combing machine a detaching roller, fulcrumed lever bearings for such roller, a rod movable in the direction of its length, a bar parallel with the rod but movable at right angles to the length of such rod, adjustable supporting means between the bar and the free ends of the roller-bearing levers, operative bell crank levers fulcrumed between the rod and bar and controlled by the sliding rod movement, and a weighting lever fulcrumed upon a bearing lever fulcrum and engaging the detaching roller.
50. In testimony whereof I have hereunto set my hand.
- JOHN WILLIAM NASMITH.
